ARRANGEMENT IN DIGESTERS ADAPTED FOR MANUFACTURING CELLULOSE AND WORKING WITH CIRCULATION EFFECTED BY A CENTRIFUGAL PUMP

Application filed May 7, 1932, Serial No. 609,916, and in Sweden July 26, 1930.

The present invention relates to an improvement in digesters adapted for manufacturing cellulose and working with circulation of liquor effected by a centrifugal pump. The object of the invention is essentially to facilitate the circulation of liquor by reducing the hydraulic losses as far as possible so as to allow the speed of the circulating liquor to be increased and, thus, the circulation to be made more efficient without the necessity of overdimensioning the apparatus of circulation.

According to the invention this is, in the first place, realized by the fact that the system of circulation is provided with a centrifugal pump having one or more spiral-shaped suction chambers arranged so as to permit the liquor, before entering into the impeller, to receive a tangential component of velocity. Thus, the liquor will be introduced into the pump evenly distributed and without impact.

To convey the liquor to the pump, two or more suction pipes may be used, because the arrangement of a number of thin pipes is easier and also cheaper, particularly when using pipes of acid-proof iron and steel.

If several suction-pipes are led to the spiral-shaped suction chamber of the pump it is of importance that these pipes are brought together in front of the said suction-chamber in such a way as to render the hydraulic losses as small as possible. According to an embodiment of the invention this desideratum is realized by the fact that the suction pipes (two or more) are connected with the pump by means of a branch pipe having a number of branches corresponding to the number of the suction pipes. At the junction or branch point said branch pipe has its branches arranged in parallel or essentially in parallel and the total cross-section of the different branches, immediately before the junction-point, is substantially equal with the cross-section of the pipe after the junction-point so as to permit the different currents to join without impact or whirling.

Other features characteristic of the invention will be more closely set forth in the

following in connection with the description of the embodiment illustrated in the annexed drawings.

Referring to the drawings, Figs. 1 and 2 show the plant as a whole, in two different side views. Figs. 3 and 4 show the centrifugal pump from two different sides, partly in section. Fig. 5 shows an embodiment of the multiple branch pipe in longitudinal section, and Figs. 6, 7 and 8 are sections on lines VI-VI, VII-VII and VIII-VIII respectively in Fig. 5.

In Figs. 1 and 2, 1 is the digester, provided with the sieve 2 and two pipes 3 extending from the latter and running within the digester. Each of said pipes 3 is, at the point in which it leaves the digester, connected to a valve 4 provided with two outlets. Connected to these outlets are two suction pipes 5 and 6. These suction pipes are joined together immediately before the inlet 8 of the centrifugal pump 7 by a multiple branch pipe 9, the design of which being more closely set forth in the following. From the pump the liquor (lye) is forced up through a heating-device 10, which is, for instance, heated by means of vapor introduced through the pipe 11 and removed through the pipe 12. Condensed water is drawn off through the pipe 13 to the steam trap 14. From the heating-device the heated liquor will then be carried off to the upper part of the digester through the pipes 15, which may be drawn in any suitable manner.

In order to obtain a circulation as strong as possible, according to the invention, the centrifugal pump is provided with one or more tangential inlets.

Figs. 3 and 4 show a tangential inlet channel 16 at each side of the pump. There is, however, nothing preventing the use of a pump having one or more tangential inlets at one side only, also several tangential inlets may be used at both sides of the pump. By means of the tangential inlet or inlets a particularly good distribution of the liquor around the entire entrance 18 of the impeller 17 is obtained, and whirlings and impacts are avoided, which would reduce

the efficiency of the pump. From the pump the liquor is forced through the outlet pipe 19 to the heating-device 10 in a manner already set forth. In Figs. 5-8 is shown an embodiment of the multiple branch pipe or Y-branch 9 joining two branch pipes 20 and 21 to a common pipe 22. As shown in Fig. 5 the two branches 20 and 21 are parallel at the point of joining with the pipe 22. The 10 cross-sections of the branch-pipes form together a section substantially equal to the cross-section of the pipe 22 immediately after the junction-point, compare Figs. 7 and 8. By such a multiple branch pipe the 15 different currents of liquor will be brought together without impact if the velocity of flowing of the liquors, at least at the junction-point of the branches, is equal in all branches. The different ends of the multiple branch-pipe have preferably a circular cross-section in order to enable the connection of the multiple branch pipe to circular pipes or connecting branches.

Finally, it should be pointed out that, of course, a multiple branch pipe according to the present invention offers the same advantages when a main current is to be divided into a number of branch currents as when the contrary course takes place.

Having now particularly described the nature of my invention and the manner of its operation, what I claim is:

1. Improvement in circulating systems for cellulose digesters wherein the reaction liquid by means of a pump aggregate is forced to circulate through the digester and an outside pipe system, consisting in the arrangement of a plurality of suction pipes conveying reaction liquid from the digester to an intake of a pump; a multiple-branch unit provided with a plurality of inlet branches and a common outlet uniting said suction pipes with said intake; the inlet channels of said multiple-branch unit being at the plane of junction parallel with each other and with the outlet channel, and adjacent channels separated by means of edged partitions; said channels being so formed that cross-sections taken immediately before and immediately 45 after said plane of junction will enclose areas with coincident interior outlines, so that the inlet channels will smoothly merge without any projections and obstructions into the outlet channel.

2. Improvement in circulating systems for cellulose digesters wherein the reaction liquid by means of a pump aggregate is forced to circulate through the digester and an outside pipe system, consisting in the arrangement of a plurality of groups of suction pipes, each group comprising a plurality of pipes, conveying reaction liquid from the digester to intakes of the pump aggregate; a multiple-branch unit provided with a plurality of inlet branches and a common outlet

uniting each of said groups of suction pipes with one of said intakes; the inlet channels of said multiple-branch unit being at the plane of junction parallel with each other and with the outlet channel, and adjacent channels separated by means of edged partitions; said channels being so formed that cross-sections taken immediately before and immediately after said plane of junction will enclose areas with coincident interior outlines, so that the inlet channels will smoothly merge without any projections and obstructions into the outlet channel.

3. The improvement in circulating systems for cellulose digesters as set forth in claim 1, and in combination with centrifugal pumps provided with spiral-shaped suction chambers.

In testimony whereof I affix my signature.

OSCAR ALBANUS WIRÉN.
